CLAIM

The ornamental design for a heat insulator cover of semiconductor manufacturing apparatus, as shown and described.

DESCRIPTION

FIG. 1 is a front, top and right side perspective view of a heat insulator cover of semiconductor manufacturing apparatus showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and

FIG. 8 is a cross sectional view taken along line 8-8 in FIG. 2 thereof; and,

FIG. 9 is a cross sectional view taken along line 9-9 in FIG. 2.
